HARVEY SLATER, OF CHICAGO, ILLINOIS, ASSIGNOR TO CHARLES F. ELMES ENGINEERING WORKS, OF CHICAGO, ILLINOIS, A CORPORATION OF ILLINOIS.

AUTOMATIC CHANGE-VALVE FOR PRESSES.

1,321,856.

Specification of Letters Patent.

Patented Nov. 18, 1919.

Application filed January 25, 1917. Serial No. 144,568.

To all whom it may concern:

Be it known that I, HARVEY SLATER, a citizen of the United States, and resident of Chicago, in the county of Cook and State 5 of Illinois, have invented certain new and useful Improvements in Automatic Change-Valves for Presses, of which the following is a specification.

My invention relates in general to a val- 10 vular device for controlling the flow of fluids under low and high pressures and particularly relates to automatically actuated valvular devices for changing from a low to a high pressure feed, in supplying 15 fluid pressure to pressure actuated machines such as the hydraulic pressure used to extract liquids from solid bodies.

With one form of such machine it is usual 20 to admit pressure thereto and to control the admission by means of a valve designed to admit the different pressures successively, first by admitting a relatively low pressure, say about 500 lbs. per square inch and, when 25 a certain compressive action has been obtained on the material in the machine to change automatically so as to admit a relatively high pressure, say about 5000 lbs. to the square inch. The valvular devices of 30 this type as heretofore constructed have contained a multitude of tortuous passageways, valves and other parts both movable and stationary which have not only necessitated a high cost of construction, but have necessitated the use of cumbersome casings 35 and expensive packing joints in order to insure a non-leaking condition under the high pressures usual in devices of this character.

Accordingly, one of the objects of this invention is to provide an automatic high 40 and low pressure control valve which will be of simplified construction, in which the usual tortuous passageways have been eliminated and replaced by straight bores and at the same time the device as a whole is constructed so that necessarily removable parts 45 are designed and assembled to attain a highly efficient valve of the class described but formed of relatively few parts and with the least possible use of material.

50 A further object of the invention is to provide a construction including a valve containing casing arranged with the least

possible number of openings thereto to minimize the possibility of leakage and arranged so that the several demountable elements 55 may be readily removed for cleaning or repairing.

Various other objects and advantages of the invention will be in part obvious from an inspection of the accompanying drawings 60 and in part will be more fully set forth in the following particular description of one form of mechanism embodying my invention, and the invention also consists in certain new and novel features of construction 65 and combination of parts hereinafter set forth and claimed.

In the drawings the figure is a longitudinal sectional view through a preferred form 70 of my invention particularly adapted for extreme high pressure.

There is shown a hollow casing 1 in the form of a rectangular block the several parts of which will be hereinafter referred to as shown in the drawing for the purpose of 75 facilitating the location of the parts in the following description. The block is provided with a vertically extending bore 2 the upper end of which is enlarged and internally screw threaded as shown at 3. An 80 insert has its lower end threaded into this enlarged portion and acts as a removable closure for the upper end of the bore. The insert includes a sleeve 5, the lower portion of which is externally threaded to engage 85 the thread 3 and which projects beyond the top of the casing 1. The sleeve is provided with a bore 6, the lower portion of which is smooth and constitutes a bearing for an enlarged cylindrical plunger 7 constituting 90 part of a change pressure valve. The upper portion of the valve is provided with a reduced stem 8 which is guided in a bore 9, in a sleeve 10 which is threaded into the upper end of the bore 6 and held in adjacent 95 position by means of a lock nut 11. The upper end of the bore 9 is closed by means of a demountable plug 12; a coiled spring 13 is housed within the bore 6 and bears upon the top of the plunger 7 and upon the 100 inner end of the adjustable sleeve 10.

The tension on the spring is adjusted by manipulating the sleeve 10 until the tension is sufficiently high to resist the unseating

action on the valve of the fluid through the high pressure inlet, and greater than the valve unseating pressure of the normal pressure through the low pressure inlet but having less tension than the combined pressures from the high and low pressure inlets when supplemented by any reactory pressure through the machine supply port.

A gland packing p is disposed between the casing 1, the shell 5 and the plunger 7. The lower end of the plunger is reduced to form an extension 14 which normally reaches across the low pressure passageway herein-after defined, and terminates in a frusto-conical valve head 15.

Opposite sides of the casing in line transversely with the valve-closed position of the extension 14 are provided with a pair of oppositely disposed openings, one constituting a low pressure inlet 16 tapped so as to be connected with a suitable source of low pressure fluid supply and the opposite opening 17 constituting the machine supply port which is similarly tapped and adapted to be connected to a hydraulic press or other machine controlled by this valve. The casing is bored transversely of the length of the bore 2 and coacts therewith to provide a low pressure passageway 18 directly connecting the inlet 16 with the port 17.

A demountable valve seat 19 of a size to be inserted through the bore when the insert 5 is demounted, is removably mounted in threaded engagement with the lower portion 35 of the bore 2 adjacent the passageway 18. The seat is provided with a centrally disposed and reduced passageway 20, the upper end of which is countersunk to form a frusto-conical seat for the frusto-conical end 40 15 of the change valve. The upper end of the seat projecting into the passageway 18 is materially enlarged to provide a massive head 21 the lower portion of which is defined by an inclined peripheral shoulder 22 designed, when the seat is screwed firmly in place, to rest on the countersunk portion 23 of the bore 2. The head of the valve seat is provided with wrench holes 24 by means of which the seat may be screwed into adjustable position. The portion of the bore below the valve seat opens through a side port 25 and constitutes an inlet for the high pressure supply. The lower end of the bore 2 is closed by means of a demountable insert 55 26 screwed into the same. This insert includes a sleeve 27 threaded into the enlarged lower end of the bore and contains a screw valve 28 provided with a conical head 29 engaging in the lower end of the passageway 60 20 in the seat to regulate the high pressure flow into the passageway 18 when the valve change head 15 is unseated. The lower end of the valve 28 projects beyond the outlines of the casing and the sleeve 27, and is provided with a square head 30 by means of

which the valve may be engaged by a suitable tool so as to move the head 29 to and from its position engaging the lower end of the valve seat 19.

In operation, it will be understood that the low pressure is admitted to the device and controlled by any suitable means such as a hand valve in the low pressure supply pipe, and the fluid under low pressure will move along the passageway 18 and across the valve extension 14 practically without interruption and directly to the machine through the port 17. This flow will continue until the actuation of the machine causes a reactory pressure therefrom to act on the large surface provided by the head of the plunger 7. This increase of pressure acting on the large area of the plunger will cause the valve 15 eventually to unseat thus opening the high pressure inlet to the machine part.

Should it be desired to control the high pressure fluid during the actuation of the machine while under the high pressure, the valve 28 can be adjusted to or from its seat, or the valve may be even closed on to the seat when it is desired to intercept the high pressure flow to the machine.

On releasing the pressure in the passageway, the spring will reassert itself and act on the change valve automatically to shut off the high pressure fluid through the valve seat. This will leave the device merely in position with the low pressure acting on the machine and this low pressure may be controlled by any approved means distinct from the device herein disclosed.

By means of a device of this character it is possible to form the change valvular mechanism of a simple block or cylinder drilled transversely to provide the low pressure passageway to the machine supply port and drilled, and counter-drilled longitudinally to provide for the housing of the inserts at opposite ends of the block or cylinder. This form of construction necessitates merely straight line drilling and the use of ordinary threading machines to thread the drilled bores so that this device may be constructed without the necessity of expensive castings or special machines.

The parts mostly subjected to wear are the valve seats and coacting valves, but in the device disclosed these parts may be made readily replaceable so that when worn, others may be substituted and this substitution may be provided merely by unscrewing the insert and positioning the valve seat in position through one of the openings so provided.

It is obvious that the tension on the spring may be readily adjusted from the outside of the casing merely by rotating the projecting portion of the adjusting sleeve in one or the other direction according as the tension is

desired to be increased or decreased. The valve seat may be adjusted in position toward and from either of the valves engaged thereby.

5 As there are but four openings in the solid casing it is obvious that the possibility of leakage has been reduced to a minimum.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I hereby claim:

1. A valvular device including a hollow casing having a straight bore extending therethrough from end to end, an insert threaded into one end of said bore, said insert including a sleeve provided with a bore constituting a plunger bearing, a change pressure valve including a plunger slidably mounted in said bearing, a spring-tension-adjusting member threaded into the sleeve bore, a coiled spring housed within the sleeve bore and bearing on said last named member and on said plunger, the inner end of said plunger being reduced to form a valve head, said casing provided with a pair of openings extending through the side thereof and opening into the casing bore at said valve head to provide a low pressure passageway connecting said openings, one of said openings constituting a low pressure inlet and the other opening constituting a machine supply port, a valve seat removably mounted in engagement with said casing bore, facing said low pressure passageway and provided with a high pressure passageway extending therethrough, said high pressure passageway normally closed by said spring pressed valve head, said casing provided with a side port opening to the casing bore to the outside of said valve seat and constituting a high pressure inlet, an insert 80 for closing the end of the casing bore to the outside of said side port, said last named insert provided with a valve for regulating the high pressure flow from said side port through said high pressure passageway in 85 the valve seat when said spring pressed valve is off its seat.

2. A valvular device including a hollow casing having a straight bore extending therethrough from end to end, an insert threaded into one end of said bore, said insert including a sleeve provided with a bore 55 constituting a plunger bearing, a change pressure valve including a plunger member mounted in said bearing, a spring-tension-adjusting member threaded into the sleeve bore, a coiled spring housed within the 60 sleeve bore and bearing on said last named member and on said plunger, the inner end of said plunger being reduced to form a valve head, said casing provided with a pair of openings extending through the side 65 thereof and opening into the casing bore at said valve head to provide a low pressure passageway connecting said openings, one of said openings constituting a low pressure inlet and the other opening constituting a 70 machine supply port, a valve seat removably mounted in engagement with said casing bore, facing said low pressure passageway and provided with a high pressure passageway extending therethrough, said high 75 pressure passageway normally closed by said spring pressed valve head, said casing provided with a side port opening to the casing bore to the outside of said valve seat and constituting a high pressure inlet, an insert 80 for closing the end of the casing bore to the outside of said side port, said last named insert provided with a valve for regulating the high pressure flow from said side port through said high pressure passageway in 85 the valve seat when said spring pressed valve is off its seat.

Signed at Chicago in the county of Cook and State of Illinois this eighteenth day of January A. D. 1917.

HARVEY SLATER.
